UNITED STATES PATENT OFFICE.

JOHN T. JANETTE, OF CHICAGO, ILLINOIS.

CENTRIFUGAL SWITCH.

1,278,936.

Specification of Letters Patent. Patented Sept. 17, 1918.

Application filed June 16, 1917. Serial No. 175,158.

To all whom it may concern:

Be it known that I, JOHN T. JANETTE, a citizen of the United States, residing at Chicago, in the county of Cook and State of

5 Illinois, have invented certain new and useful Improvements in Centrifugal Switches, of which the following is a specification.

This invention relates more particularly to improvements in switches which are used 10 in connection with alternating current motors for introducing and cutting out the split phase starting coils or elements.

The objects of this invention are to provide a centrifugal switch of the character 15 indicated which will be light, inexpensive in construction, and durable and efficient in operation; to provide a switch of this character which is constructed of comparatively few parts which may be readily assembled; 20 to provide a switch having an auxiliary contact where the final break is made in order to prevent arcing or burning of the main contact; and in general, to provide such an improved structure as will appear more fully 25 from the following description. In the accompanying drawings illustrating this invention:

Figure 1 is a plan view of the switch as applied to a motor;

30 Fig. 2 is a front view of the same;

Fig. 3 is a fragmentary view showing the switch open; and,

Fig. 4 is a sectional view taken on the line 4—4 of Fig. 2.

35 The general construction of single phase alternating current motors having split phase starting coils is well understood in the art, and is therefore not illustrated. In the accompanying drawings, 5 indicates the motor frame and 6 the shaft which engages with a bearing 7 in the frame, these parts being of any ordinary or preferred form of construction. The centrifugal switch is mounted on the shaft 6 and rotates there-

40 with. This switch comprises two rings or disks 8 and 9 which are insulated from each other. These disks are engaged respectively by brushes 10 and 11 which are connected with the circuit leading through the starting coils, so that when a connection is made 45 between these two rings or disks, the current will be supplied to the coils. A substantially semi-circular switch 12 is pivoted at 13 to the disk 9, and its free end is adapted to engage and make electrical connection 50 with a contact 14, which is connected by

means of a pin or rivet 15 with the disk 8. The contact 14 and rivet 15 are insulated from the disk 9, as indicated in Fig. 4.

The contact arm or switch arm 12 is urged into contact position by a spring 16, one end of which engages with a shoulder 17 in said arm, the other end being secured in a plate 18 which is fastened to the disk 9 by means of rivets 19, or in any other suitable 60 manner. The free end of the arm 12 is provided with a slot 20 to receive a guide pin 21 for limiting the movement of said end. A wiper or auxiliary contact 22 is pivoted at 23 to a projection on the arm 12. This 70 wiper has a finger 24 which engages with a hole 25 in the arm for limiting the movement of said wiper. The forward or free end of the wiper is curved or shaped, as indicated, at 26 for making wiping contact 75 with a projection 27 which extends outwardly from the stationary contact 14. An insulating plate 28 separates the contact points from the disk 9, and prevents any arcing to the disk. 80

The operation of the switch is as follows: When the motor is at rest, the spring 16 swings the arm 12 so that the end thereof is in engagement with the contact 14, and thereby closes the circuit from the disk 9 to 85 the disk 8, and consequently closes the circuit through the starting coils. When current is supplied to the motor and the speed increases to a predetermined amount, the free end of the arm 12 moves outwardly by 90 the centrifugal force, thereby opening the circuit through the main switch contacts which are the end of the arm and the contact 14. The free end of the wiper 22, however, remains in contact with the lug 27, so 95 that the circuit is not broken until the wiper passes away from such lug. This wiper is pivoted so that the centrifugal force tends to hold its free end in engagement, and the positions shown in dotted lines in Fig. 2 indicate the positions of the parts just previous to the breaking of the circuit through the auxiliary contact. When the end of the arm 12 reaches the position shown in Fig. 3, the wiper 22 has broken the contact with the 100 lug 27, and the spark formed by breaking the circuit will be between the wiper and the lug, thereby protecting the main switch contacts from injury. When the motor comes to rest, the spring 16 will swing the free end 110 of the arm 12 back to its original position, the contact first being made through the

wiper 26 riding over the lug 27, and finally through the main contact. The finger 24 holds the wiper 22 in contact position and also in proper position for making contact 5 when the arm swings inwardly. It will be noted that the auxiliary contact operates entirely by centrifugal force, so that no additional spring is necessary.

From this description, it will be seen that 10 I provide an exceedingly simple and efficient centrifugal switch, the parts of which may be very readily manufactured, and this switch has proven highly efficient and satisfactory in practice. It will, however, be observed that changes may be made in the 15 details of construction without departing from the spirit of this invention and, therefore, I do not wish to limit myself to the exact construction or arrangement herein shown or 20 described, except as specified in the following claims, in which I claim:

1. A centrifugal switch for motors, comprising two co-axial contact disks 8 and 9 insulated from each other, a contact 14 connected with the disk 8 and arranged on the face of the disk 9, a contact arm 12 pivoted at one end to the disk 9 and adapted to make contact with the contact 14, a spring tending to hold said contact arm in engagement with 25 the contact, a lug on said contact, and a wiper pivotally mounted on said contact arm and having limited movement with respect thereto, said arm and wiper being adapted to act under the influence of centrifugal 30 force, the arrangement being such that the connection will first be broken between the contact arm and the contact 14, and will finally be broken between the wiper and said 35 lug.

2. In a centrifugal switch, the combination 40 of two contact rings insulated from each other, a contact electrically connected with one of said rings and arranged adjacent to the face of the other ring, a substantially 45 semi-circular switch pivotally mounted at one end on the other ring and having its free end adapted to engage with said contact, a spring tending to hold the switch in engagement with the contact, a projection 50 on said contact, a wiper pivotally mounted on the free end of said switch and having a curved end for engagement with said projection, an arm on the opposite end of said wiper which engages with a hole in the 55 switch for limiting the movement of the wiper, the arrangement being such that

when the switch is open, the final break will be made between the wiper and the projection.

3. The combination with a rotatable shaft, 60 of a contact ring or disk mounted thereon, a second contact ring or disk arranged adjacent to the first-named disk and insulated therefrom, a contact arranged adjacent to said last-named disk and insulated therefrom, an electrical connection between the contact and the first-named disk, a switch arm pivoted at one end to said second disk with its free end adapted to engage with 65 said contact, a flat spring having one end secured to said second disk and the other end engaging with the opposite end of said switch arm and tending to hold the free end of the switch arm in engagement with the contact, a projection from said contact, and 70 an auxiliary contact pivotally mounted on the free end of said switch arm and having limited movement with respect thereto, said auxiliary contact having a curved terminal for engagement with said projection, the 75 arrangement being such that when the switch opens under the influence of centrifugal force, the final break is made between the auxiliary contact and said projection.

4. In a centrifugal switch, the combination 80 of a relatively fixed contact, a contact arm which is adapted to be actuated by centrifugal force to open the switch, means tending to hold the contact arm in engagement with the fixed contact, a stop for limiting the movement of the arm, and an auxiliary contact member coacting with the arm and fixed contact to make the final break 85 between the arm and the fixed contact when the switch opens.

5. In a centrifugal switch, the combination 90 of a rotatable member, a relatively fixed contact mounted on said member, a substantially semi-circular switch arm having one end pivoted to the rotatable member on the 95 opposite side of the axis from the contact, the free end of said arm being adapted to engage with said contact, resilient means for holding said arm in engagement with the contact, said arm having a slot therein, a 100 stop pin for engagement with said slot, and an auxiliary contact member coacting with said arm and said contact, and adapted to make the final break when the switch is 105 opened.

JOHN T. JANETTE.
